Primary Examiner — Catherine Ho*Assistant Examiner* — Natalya M Rapundalo(74) *Attorney, Agent, or Firm* — Dinsmore & Shohl LLP(57) **CLAIM**

The ornamental design for a cooktop grate, as shown and described.

DESCRIPTION

FIG. 1 is a perspective view cooktop grate showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines show portions of the cooktop grate that form no part of the claimed design.
